APPARATUS FOR AUTOMATIC WEIGHING

Leon J. Nowak, Jr., Park Ridge, Ill.

Application August 24, 1953, Serial No. 375,901

13 Claims. (Cl. 249—38)

The invention relates to an improvement in weighing, and has for one purpose to provide an improved automatic weighing machine.

Another purpose is to provide an improved apparatus for feeding automatic weighing machines.

Another purpose is to provide an improved weighing machine which includes improved feed apparatus.

Another purpose is to provide an improved control system for insuring accurate feeding of automatic weighing machines.

Other purposes will appear from time to time in the course of the specification and claims.

The invention is illustrated more or less diagrammatically in the accompanying drawings, wherein:

Figure 1 is a partial side elevation, with parts broken away and parts in section;

Figure 2 is an end elevation of the structure shown in Figure 1;

Figure 3 is a vertical section on the line 3—3 of Figure 2;

Figure 4 is a partial end view, on an enlarged scale, of the structure shown in Figure 2, with parts broken away and parts in section.

Figure 5 is a partial elevation, on an enlarged scale, of the structure shown in Figure 3, with parts broken away and parts in section;

Figure 6 is a horizontal section on the line 6—6 of Figure 5;

Figure 7 is a horizontal section on the line 7—7 of Figure 1;

Figure 8 is a detail of the structure shown in Figure 1; and

Figure 9 is a schematic wiring diagram.

Like parts are indicated by like symbols throughout the specification and drawings.

Referring to the drawings, 1 indicates an upright frame member or supporting post. It may be mounted on any suitable base or bottom member, not herein shown. Secured to or about it, somewhat below its upper end, is a lower bracket A. Secured to it, adjacent its upper end, is an upper bracket B. Considering, first, the lower bracket A, as shown, for example, in Figure 7, it is shown as including a sleeve 2 and arm 3 extending outwardly therefrom and carrying a control box 4 which will later be described. Extending generally at right angles to the arm 3 is a cross-bar 5. Shown as extending from the cross-bar is an extending arm 6, lying generally in a plane generally parallel with the plane of the arm 3. It carries at its outer end a dash-pot structure, generally indicated as 7, which will later be described.

Mounted upon the cross-bar 5 is a weighing beam structure, including the pivot 8, the ends of which are received in suitable bearings 9, 10 on the cross-bar 5. The weighing beam structure includes a sleeve 11 through which the pivot 8 passes. 12 is any suitable securing and adjusting element or screw therefor. Extending in one direction from the weighing beam sleeve 11 is a

2

pair of arms 13, which receive or are formed integrally with a generally semi-circular fork 14. 15 is the calibrated bar of the weighing beam, which extends in the opposite direction from the arms 13 and the fork 14, and 5 which is shown as received in and secured to the stub 16 of the weighing beam sleeve 11. It may be suitably calibrated, as at 17, and carries the longitudinally adjustable weight 18 which surrounds it. The weight 18 may be secured in adjusted position, for example, by 10 a thumb screw 19, and is shown as having a blade 20 with a terminal edged portion 21 adapted for accurate reading of the calibration 17. The movement of the calibrated bar 15, and thus of the entire weighing beam structure, is held within predetermined limits, for example, by 15 the U-shaped limit member 22. The limit member is shown as mounted upon the arm 6 of the cross-bar 5. An end cross-piece 24 is mounted at the end of the calibrated bar 15, and has secured to it the downwardly extending pin 25 secured to any suitable bell 20 7a in the dash-pot 7. It will be understood, therefore, that, with an adequate supply of liquid in the dash-pot 7, movement of the calibrated bar 15, and thus of all parts of the weighing beam, is suitably damped, unintended sharp movements being prevented.

25 The weighing beam fork 14 has, at its ends, bearing blades 14a. Mounted within the fork 14 is a bucket or weighing member 26. The bucket is shown as having an having an open top, a generally cylindrical body, and an open bottom. Intermediate the top and bottom of 30 the body I employ bearing bosses 26a, having inverted pockets 26b, each of which has a downwardly face bearing block 26c. These blocks, opposed to the upwardly directed bearing blades 14a, provide for the support of the bucket or weighing container 26. The bottom of the 35 bucket is controllably closed by the hinged bucket closure 27. For example, it may be provided with brackets 28 pivoted to any suitable pivot assembly or bracket 29 on a lower portion of the bucket 26. It will be noted, as in Figure 1, that the lower edge of the bucket 26 lies 40 in a plane inclined to the axis of the bucket, the bucket closure 27 being hinged at its upper or higher portion.

The bucket closure can be held in the closed or full-line position in which it is shown in Figure 1, by the below-described control assembly mounted in or on the 45 control box 4 on the arm 3 of the lower bracket A. This structure will be described later, in detail.

It will be understood that material is delivered into the top of the bucket 26 from suitable feeding means, later described, which are mounted on the upper bracket 50 B. It will further be understood that I may employ a discharge hopper 30 with its suitable discharge spout 31. It will be understood that the particular receiving or discharge hopper shown is practical, but that any other suitable means for receiving the discharge from the 55 bucket 26 may be employed.

Considering, now, the means for receiving the material to be weighed, and for feeding it to the bucket 26, I illustrate a feed hopper 35 mounted on or unitary with the upper bracket B, and having, at its lower convergence, a 60 pair of generally vertical, generally parallel side walls 36. Within and between the walls 36 are downwardly extending liners or extensions 37, the members 36 and 37 defining a space open at the ends. Pivoted to the walls 36 are a pair of pivoted shutters 38, each being pivoted at its upper end, as at 39, at opposite sides of a lower portion of the receiving hopper 35, and downwardly converging toward each other. These shutters, with the liner or wall members 37, define a discharge aperture which can be adjusted by adjusting the angular position 65 of the shutters 38. The adjustment can be made by the structure shown in Figure 2, in which the right-hand shutter 38 has secured to it an arm 40 with a pointer 70

40a and an actuating knob **40b**, the pointer **40a** being movable along any suitable calibrated indicator segment **40c**. The opposite or left-hand shutter **38** has secured to it a shorter lever **41** which, in turn, is secured to the lever **40** by a slot and pin connection, including the pin **41a** and the slot **41b**. Thus, when the user raises or lowers the assembly by moving the knob **40b** upwardly or downwardly, he moves the shutters **38** in unison, and varies the discharge opening. **42** is a manual gate or slide, manually movable into or out of closed position by its exterior portion, which ends in a bent handle member **42a**.

It will be understood that the above-described structure provides a controllable aperture for delivering material fed into the receiving or feed hopper **35** toward a final and accurately operable shut-off element. This element, shown, for example, in Figures 3 and 5, includes a segmental curved or partly cylindrical blade **44**, to which is secured a side arm **44a** pivoted as by a hub **44b** rotating about a pivot pin **44c** extending outwardly from the receiving or feed hopper **35**. The shut-off element **44** is actuated or moved by suitable means, such as the solenoid generally indicated at **C** in Figure 3. The solenoid may, for example, include the coil **45**, the plunger or stem **45a**, and any suitable link or connection **45b** pivoted to the side arm **44a**, as at **45c**. It will be understood, therefore, that, by energizing or deenergizing the coil **45** of the solenoid **C**, the shut-off element **44** may be rotated about its pivot into and out of cut-off position. As will be seen in Figure 3, the shut-off element **44** has a substantial free, lower portion, which, when the shut-off element is in the full-line position of Figure 3, extends within a three-sided flexible apron **46**.

The flexible apron includes parallel side walls **46a** and **46b**, connected by a preferably flexible end wall **46c**. The apron may be stiffened or supported at top and bottom by upper and lower bent strips **46d** and **46e**. It may be held in position by any suitable means. I show, for example, an apron clamping spring, generally indicated at **47**, which may be secured, as shown in Figure 3, by a securing screw or screws **47a**. The spring has a bent portion **47b** which engages the upper end of the flexible apron, and a lower end **47c** which engages the lower end of the flexible apron, and both supports and positions the flexible apron. It will be understood that the shut-off element **44** engages only the intermediate flexible part of the apron **46**, and makes a substantially tight connection therewith. The otherwise open side of the space surrounded by the flexible apron **46** and lying above the shut-off element **44** when that element is in closed position, is closed by an additional flexible member, herein indicated as a brush **48**. This brush is suitably clamped in position, for example, by the clamping spring **48a**, secured by a screw or screws, as at **48b**. It will thus be understood that when the shut-off element **44** is moved to the full-line or closed position of Figure 3, it underlies and downwardly closes a space which is surrounded on three sides by the flexible apron **46**, and on the fourth side by the brush **48**. When the element **44** is moved into the open position, for example, by the action of the solenoid **C**, all material previously resting on the shut-off element **44** then drops into the open top of the bucket **26**. It will be understood, of course, that the hinged bucket closure **27** is, at that time, in the closed position in which it is shown in Figure 1, the control details being below described.

In order to keep the hinged bucket closure **27** in the closed position, when a charge of material is being released by the shut-off element **44**, I employ the following means: The hinged bucket closure is provided with a bracket **27a** to which is pivoted a bucket closure control link **50**. This link is shown as having an upper end of characteristic form, as will appear in Figures 5 and 8. As shown, for example, in Figure 8, its upper end is provided with a curve or bend **50a**, the outer end of which is pivoted, as at **50b**, to a control segment **51**. As will be clear from Figure 8, the bend **50a**, when the parts are

in the position shown in Figure 8, surrounds the axis of the segment **51** and engages the pin **51a**, which is on such axis. The pin **51a** is mounted on or secured to a bracket **51b** on the bucket **26**. **51c** is any suitable ball bearing assembly surrounding the pin **51a** and permitting rotation of the segment **51** thereabout, with a minimum of friction, and without binding. It will be noted that when the hinged bucket closure **27** is in the closed position, the pivot **50b** is over center in relation to the pivot or pin **51a**, and any application of weight to the hinged bucket closure **27** will tend to hold it in closed position, owing to the relation of the center **51a** to the upper pivot **50b** of the bucket closure control link **50** and to its lower pivot **27b**. Thus the segment **51** provides a releasable means for holding the hinged bucket closure **27** in the closed position, and for preventing its unintended opening during the delivery of material to the interior of the bucket **26**.

In order to open the hinged bucket closure **27** or to permit it to swing downwardly to the full-line open position in which it is shown in Figure 3, I provide the following arrangement: The control segment **51** carries a pin **51e** in alignment with the plunger **52a** of the solenoid **52**. The solenoid is carried in or on the control box **4**. When the coil of the solenoid **52** is energized, the plunger **52a** is moved against the pin **51e** and thereby moves the control segment **51** about its axis. Referring to the position of the parts in Figure 5, the solenoid plunger **52a**, when it moves upwardly against the pin **51e**, imparts a counter-clockwise rotation to the control segment **51**, referring to its position in Figure 5, and moves the axis or center **50b** to the left of the pin **51a**. Thus the weight of the charge or load in the bucket **26** is then able to move the hinged bucket closure **27** from the closed to the open position, and the weighed load is discharged, for example, into the hopper **30** and through the discharge spout **31**. As will be clear from Figure 3, the pivoted shutter **27** carries a weight **27x**, which tends to move the hinged bucket closure back to the closed position when it is free from the weight of the discharged material. The control segment **51** also constitutes a weight, and tends to return the hinged bucket closure **27** to its original position. As will be clear, for example, in Figure 3, the control segment **51** is weighted or solid, as at **51x**, and is cut away or lightened, as at **51y**. Thus, notwithstanding the relative location of the various pivots or centers above discussed, when the load of the bucket has been released, the heavier portion **51x** of the control segment cooperates with the weight **27x** of the hinged bucket closure to return that closure to closed position, and when it has returned to closed position, with the solenoid plunger **52a** in its withdrawn position, the bucket closure control link **50** returns to the position in which it is shown, for example, in Figure 5, and the hinged bucket closure then remains in its closed position until the solenoid **52** is again energized.

In connection with the necessary controls for maintaining the desired sequence of actions or steps, an additional feature of the control segment must be discussed. It carries a permanent magnet **53**, shown, for example, in Figure 4. The parts are so proportioned that when the hinged bucket closure **27** is in the closed position in which it is shown in Figure 1, the permanent magnet **53** is in alignment with a mercury switch, generally indicated at **54**. This switch includes a glass bulb **54a**, a pool of mercury **54b**, and a spring member **54c**, which is normally biased to the open or full-line position in which it is shown in Figure 4. The spring **54c** also carries a small plate or metal body **54d**, adapted to be attracted by the permanent magnet **53** to move the spring **54c** from the full-line to the dotted-line position of Figure 4, and thus to control the circuit. In other words, when the hinged bucket closure **27** is in the closed position, the permanent magnet **53** operates to close the above-described mercury switch, the permanent magnet **53** at that

time being in the dotted-line position of Figure 4, and the bucket 26 being empty. As material is delivered into the bucket 26 and against the still-closed hinged bucket closure 27, the bucket lowers sufficiently eventually to move the permanent magnet 53 from the initial dotted-line position of Figure 4 to the full-line position. When it reaches the full-line position of Figure 4, or some critical position, then the spring 54c returns to the full-line position of Figure 4, and the circuit is broken. The parts are so proportioned that this takes place when the desired or predetermined load is in the bucket. It will be understood, of course, that the parts are precisely formed or adjusted to obtain this result.

As will be clear, for example, from Figures 1, 2 and 7, I provide means for maintaining the bucket 26 in proper vertical position without subjecting it to constraint. I illustrate, for example, the upwardly extending post 100 mounted on the arm 6. Pivot to its upper end, and to the bucket 26, is a link 101. This connection insures that the bucket 26 will be held against any damaging deflection from its desired upright position and movement, while allowing for any uneven weight distribution in the bucket.

In considering the functions or operations of the various structures above described it is well now to consider the wiring diagram of Figure 9. Let us assume that the parts are initially in the position of Figure 1, with the shut-off element 44 in the closed position and with the hinged bucket closure 27 in the closed position, assuming, also, that the bucket 26 is empty. The wiring diagram includes a relay assembly, generally indicated at AA. It includes a coil 60, a movable switch member 60a, contacts 60b and 60c, and a spring or biasing means 60d, which normally tends to hold the switch member 60a against the contact 60b. When the coil 60 is energized it is effective against the spring 60d to move the switch member 60a away from the contact 60b and against the contact 60c. Assume that the hinged bucket closure 27 has moved from the open position of Figure 3 to the closed position of Figure 1. This aligns the permanent magnet 53 in the dotted-line position of Figure 4, and closes the mercury switch. When the mercury switch 54 is closed, the coil 60 is energized and the switch 60a then is in circuit closing relation with the fixed contact 60c, and also energizes the coil 45 of the solenoid C. Thus the previously closed shut-off element 44 is moved by the solenoid C to the open position, and material is free to flow into the bucket 26. As this material continues to flow, the bucket is gravitationally depressed, and the permanent magnet 53 is moved from the dotted-line to the full-line position of Figure 4. The parts are so related that this does not take place until a predetermined, precisely controlled, charge of material is in the bucket 26, and is gravitationally resting upon the hinged bucket closure 27. The movement of the permanent magnet 53 from the dotted-line position to the full-line position of Figure 4 permits the mercury switch 54 to break the above-described circuit, de-energizing the relay coil 60. This also de-energizes the coil 45 of the solenoid C, and the shut-off element 44 moves by its weight into the fully closed position. When the coil 60 is de-energized, the movable switch member 60a moves against the contact 60b, and partially completes a circuit through the solenoid 52. This circuit can be completed by closing the manually controllable switch B, B, shown at the right of Figure 9. It will be understood, of course, that, if I wish, I may provide other means, automatic, or not, for closing this circuit. However, Figure 9 illustrates an operative circuit in which all that the operator has to do, to maintain a sequence of precisely weighed charges of material, is to press the manual button 65 when he wishes the bucket 26 to discharge. It should be kept in mind that when the plunger 52a strikes the pin 51e of the control segment 51 it rotates the control segment in a position in which the permanent magnet 53 is re-

moved from the metal plate 54d on the spring 54c in the mercury switch 54, and does not operate it. It is not until the control segment 51 has again been rotated through a retrograde rotation that the permanent magnet 53 is again alignable with the mercury switch 54, with the control segment in the position in which it is shown in Figure 5.

Whereas I have described and shown a practical and operative structure, it will be understood that many changes may be made in size, shape, number and disposition of parts. It will be understood, also, that whereas I have described a practical method of feeding, weighing and discharging very precisely weighed charges of material, I may also vary the nature and order of the steps taken to obtain the desired result.

The use and operation of the invention are as follows:

The simple mechanism herein described can be supported on any suitable support, for example, the upright frame member or post 1. The lower bracket A supports the weighing beam, and the bucket or weighing container 26, together with the control mechanism for controlling the hinged bucket closure 27. The upper bracket B supports the receiving or feed hopper 35 with its shut-off element 44 and its associated parts and control. Initially, a charge of material delivered through the hopper 35 is caused or allowed to build up above the shut-off element 44, when that gate is in the closed position. The shut-off element can only open when the hinged bucket closure 27 is in the closed position. When it does open, for example, by action of the solenoid C, it delivers a charge of material through the flexible apron 46 into the top of the bucket or weighing container 26. Since this feeding action can take place only when the hinged bucket closure 27 is closed, the material in the space above the shut-off element 44, and the material which continues to be fed from or through the hopper 35, build up weight in the bucket or weighing container 26. Since the bucket is mounted in the fork of a weighing beam, the beam is gradually elevated, and the bucket 26 gradually lowers. Any sudden movement is prevented by the dash-pot 7 with its dash-pot bell 7a. The desired weight is adjusted or controlled by movement of or setting of the weight 18. Additional balancing weights or adjusting weights 18x may be employed, on the U-shaped support 18y, shown in Figure 7. But whatever means are employed, it will be understood that the continuing feed of material into the bucket 26 gradually lowers the bucket, and, with it, the control segment 51 mounted thereon. Since the control segment, when the hinged bucket closure 27 is closed, is in such position as to align the permanent magnet 53 with the metal body 54d on the spring 54c of the mercury switch 54, that switch is kept closed until the bucket 26 has been gravitationally lowered by the increasing weight in the bucket 55 to a point at which the permanent magnet 53 ceases to attract the metal body 54d. When this critical point is reached, the spring 54c moves to the full-line position of 54, and the mercury switch 54 is then open. In effect, the opening of the switch 54 conditions the hinged bucket 60 closure 27, or arranges the circuits to permit opening of the closure. The closure 27 will stay, against gravity, in its closed position, as long as the control segment 51 remains in the position in which it is shown in Figures 1, 5 and 8. However, if the user then elects to dump 65 the charge, or if suitable automatic or intermittently operating means are provided, the control segment 51 is moved to the release position in which it is shown in Figure 3, and the weight of the charge of material being weighed is then effective to move the hinged bucket closure 27 to the open position in which it is shown in Figure 3. I find one convenient way to open the closure 27 and to release the charge is to provide electromagnetic means for moving the control segment 51 to the release position. I illustratively show, to attain that purpose, a solenoid 52 with its plunger 52a. The coil

of the solenoid 52 can be energized, as shown in Figure 9, by closing the switch B, B. This "push-button" control is perfectly practical, but any other suitable control or actuating means can be employed. As soon as the hinged bucket closure 27 has swung to the release or discharge position of Figure 3, it is freed from the gravitational thrust of the discharged material. It then swings to the closed position, due to the operation of its weight 27x and the weighted portion 51x of the control segment 51. This returns the permanent magnet 53 to the dotted-line position of Figure 4, and, until a flow of material into the bucket has again lowered the bucket or weighing container 26, the permanent magnet 53 holds the mercury switch 54 closed.

It should be kept in mind that no material escapes the shut-off element 44 unless and until the hinged bucket closure 27 is in the closed position. It should also be kept in mind that, as soon as the permanent magnet 53 releases the mercury switch 54 to the open position, the shut-off element 44 drops to the closed position, and no further discharge of material into the bucket 27 takes place until after the release of the weighed charge and the return of the hinged bucket closure 27 to the closed position.

I claim:

1. In a weighing assembly, a base, a weighing beam on said base, a bucket body on said weighing beam, means for feeding into the bucket body charges of the material to be weighed, a bottom closure movably mounted on the bucket body, a link pivoted at its lower end to the movable closure, a control member pivoted to the bucket body, the upper end of the link being eccentrically pivoted to the control member, the so formed pivotal connections having parallel axes, the pivotal connection between the link and the movable closure, and between the control member and the bucket body being so related that when the movable closure is in the closed position, the pivotal connection between the upper end of the link and the control member is over center with relation to the pivotal connection between the control member and the bucket body, and the movable closure is thereby held against unintended release by action of gravity from its closed position, and electromagnetic means for moving the control member to the release position, and for thereby moving the bottom closure to the open position, whereby to permit the discharge of weighed material from the bucket body, said electromagnetic means being operative when a predetermined weight of material is in the bucket body.

2. The structure of claim 1 characterized by and including manually operable means for actuating the electromagnetic means for moving the control member to the release position.

3. The structure of claim 2 characterized by and including a circuit for the electromagnetic means for moving the control member to the release position, means responsive to the weight of material in the bucket body adapted to condition said circuit for the operation of said electromagnetic means, in response to a predetermined weight of material in the bucket body, and additional means for actuating the electromagnetic means after the circuit is thus conditioned.

4. The structure of claim 3 characterized by and including a circuit for the electromagnetic means for moving the control member to the release position, means responsive to the weight of material in the bucket body adapted to condition said circuit for the operation of said electromagnetic means, in response to a predetermined weight of material in the bucket body, and additional means for actuating the electromagnetic means after the circuit is thus conditioned, said additional means being manually operable.

5. In a weighing assembly, a base, a weighing beam on said base, a bucket body on said weighing beam, means for feeding into the bucket body charges of the material

to be weighed, a bottom closure movably mounted on the bucket body, a link pivoted at its lower end to the movable closure, a control member pivoted to the bucket body, the upper end of the link being eccentrically pivoted to the control member, the so formed pivotal connections having parallel axes, the pivotal connection between the link and the movable closure, and between the control member and the bucket body being so related that when the movable closure is in the closed position, the pivotal connection between the upper end of the link and the control member is over center with relation to the pivotal connection between the control member and the bucket body, and the movable closure is thereby held against unintended release by action of gravity from its closed position, a feed delivering member on said base, having a delivery aperture adapted for the delivery of material into the bucket body, a cut-off gate having a portion adapted to close said delivery aperture, electromagnetic means for moving the control member to the release position, and for thereby moving the bottom closure to the open position, whereby to permit the discharge of weighed material from the bucket body, said electromagnetic means being operative when a predetermined weight of material is in the bucket body, a circuit for said electromagnetic means, means responsive to the weight of material in the bucket body adapted to cause the movement of the cut-off gate to closed position and to condition said circuit for the operation of said electromagnetic means, and additional means for actuating the electromagnetic means after the circuit is thus conditioned.

6. In combination, in a weighing assembly and control means therefor, a weighing support, a charge weighing bucket on said support, said bucket having an opening and a movable closure therefor, means for delivering to the bucket material to be weighed, a control member movable on the bucket and an actuating connection between the control member and the closure, the control member having a magnet thereon, a switch positioned adjacent the path of movement of the bucket, the switch having a contact responsive to the magnet, the magnet being opposed to and aligned with the switch and switch contact when the closure is in closed position and the bucket is empty, the parts being positioned and adapted for the movement of the magnet to inoperative position in relation to the switch in response to the movement of the bucket by a predetermined weight of material in the bucket.

7. In combination, in a weighing assembly and control means therefor, a weighing support, a charge weighing bucket on said support, said bucket having a discharge opening and a movable closure therefor, means for delivering to the bucket material to be weighed, a control member movable on the bucket and an actuating connection between the control member and said closure, and means for controlling the flow of material to the bucket initiated by changes in the position of the control member.

8. In combination, in a weighing assembly and control means therefor, a weighing support, a charge weighing bucket on said support, said bucket having a discharge opening and a movable closure therefor, means for delivering to the bucket material to be weighed, a control member movable on the bucket, an actuating connection between the control member and said closure, and means for controlling the flow of material to the bucket in response to changes in position of the control member, said means being formed and adapted to prevent the initiation of flow of material to the bucket when said closure is in partly opened position.

9. The structure of claim 8 characterized by and including means for preventing the initiation of flow of material to the bucket when said bucket is below its unloaded position of maximum elevation.

10. In combination, in a weighing assembly and control means therefor, a weighing support, a charge weighing bucket on said support, said bucket having a discharge

opening and a movable closure therefor, means for delivering to the bucket material to be weighed, a control member movable on the bucket and an actuating connection between the control member and said closure, and means for controlling the flow of material to the bucket responsive to changes in position of the control member with the bucket.

11. In a feed cut-off assembly for weighing devices and the like, a feed delivering member having wall portions defining a delivery aperture, a flexible depending apron surrounding and extending below said aperture, said apron including flexible wall members extending about three sides of the said delivery aperture, and a cut-off gate transversely movable into and out of said apron at a point substantially above the lower edge of the apron, said cut-off gate being positioned and dimensioned to maintain a sealing contact with the flexible apron.

12. The structure of claim 11 characterized by and including an additional flexible member positioned to overlie and contact the upper surface of the cut-off gate when the cut-off gate is moved into its cut-off position in contact with the flexible apron, said additional flexible member being positioned and adapted, with the flexible apron, completely to surround the path of material delivered from the passage aperture, and closely to overlie the cut-off gate whereby, upon withdrawal of the cut-off gate, said last mentioned flexible member wipes the upper surface of the cut-off gate.

13. The structure of claim 11 characterized in that the cut-off gate is generally arcuate and is pivoted for movement about an axis aligned substantially above the delivery aperture, whereby the cut-off gate itself, in cooperation with the flexible apron, is positioned and adapted to prevent the unintended escape of material delivered through said aperture when the cut-off gate is in non-feeding position.
